UNITED STATES PATENT OFFICE.

HERMANN HAYSEN, OF SHEBOYGAN, WISCONSIN.

DESIGN FOR A ONE-PIECE LAVATORY.

SPECIFICATION forming part of Design No. 30,573, dated April 18, 1899.

Application filed March 23, 1899. Serial No. 710,257. Term of patent 7 years.

To all whom it may concern:

Be it known that I, HERMANN HAYSEN, a citizen of the United States, residing at Sheboygan, in the county of Sheboygan and State 5 of Wisconsin, have invented and produced a new and original Design for a One-Piece Lavatory; and I do hereby declare the following to be a full, clear, and exact description of the same, reference being had to the accompanying 10 drawings, forming a part thereof.

In the said drawings, Figure 1 is a plan view, and Fig. 2 is a vertical sectional view taken on the line 2 2 of Fig. 1, of a one-piece lavatory embodying my new design.

15 My design relates to the new and original shape or configuration of the article.

The leading or essential feature consists in the unitary design for a one-piece lavatory made the subject of illustration, comprising 20 the peculiar and novel shape of the back and shelf, as hereinafter more particularly described.

The back A A rises vertically from the shelf B, the latter being horizontally disposed 25 and having a right-angled rear edge, the said back being therefore right-angled and with its top edge curved over backward on a circular line, as indicated in section between a and b in Fig. 2, the forward ends of the parts 30 A A being rounded down between the points c d, and below the latter point d being vertical, the described curved top edge continu-

ing continuously over the top edge, rounded forward corners, and vertical ends of the said back A A. The front of the shelf B is formed 35 on a rounded line between the points e e and on straight lines between the points e and f on each side of the said central rounded line, and rising from the plane of the shelf B is a continuous rounded border g, extending all around 40 the front of said shelf from f to f, semicircular in cross-section above the plane of the shelf B, but with its outer part extending below said plane and flaring outwardly, as shown at h, the lower edge of this flared portion h 45 coinciding with the lower edge of the vertical ends of the back A A.

A minor feature of my said design includes the shape and arrangement of the bowl C, which is of elliptical shape at the top and arranged so that the longest curved line of the ellipse is parallel with the curved line of the front of the shelf B between the points e e. 50

Having thus described my invention, what I claim as new, and desire to secure by Letters 55 Patent, is—

The design for a one-piece lavatory, substantially as herein shown and described.

In testimony whereof I affix my signature in presence of two witnesses.

HERMANN HAYSEN.
